UNITED STATES PATENT OFFICE.

MERRICK F. WILSON, OF CHICAGO, ASSIGNOR OF ONE-HALF TO CHARLES R. STEELE AND V. CLARENCE PRICE, BOTH OF WAUKEGAN, ILLINOIS.

PAPER-BOX MACHINE.

SPECIFICATION forming part of Letters Patent No. 369,900, dated September 13, 1887.

Application filed June 3, 1885. Serial No. 167,540. (No model.)

To all whom it may concern:

Be it known that I, MERRICK F. WILSON, a citizen of the United States, residing at Chicago, in the county of Cook and State of Illinois, have invented certain new and useful Improvements in Paper-Box Machines, which are fully set forth in the following specification, reference being had to the accompanying drawings, in which—

10 Figure 1 is an elevation of a machine embodying my invention; Fig. 2, a plan view of the same; Fig. 3, an enlarged sectional view taken on the line $x-x$ of Fig. 2; Fig. 4, a sectional view taken on the line $y-y$ of Fig. 1; 15 Fig. 5, a sectional view taken on the line $z-z$ of Fig. 1; Fig. 6, a detail view, partly in section, of the end of one of the spindles, showing one of the clamping-disks and its centering device; Fig. 7, a similar view of the end 20 of the other spindle, showing the other clamping-disk and the box-holder; Fig. 8, a detail view of the yoke which operates the box-holder; Fig. 9, a face view of one of the clamping-disks; Fig. 10, a detail plan view of the 25 mechanism for communicating motion to the spindle; Fig. 11, a view illustrating the roller-tool employed in finishing the box, and Fig. 12 a sectional view of the complete box which my machine is designed to produce.

30 Like letters refer to like parts in all the figures of the drawings.

My invention relates to paper-box machines and more particularly to that class of machines wherein an already-formed box-body is 35 united to the box-bottom by means of a covering of paper previously coated with paste, its object being to provide means whereby the operation of joining the body and bottom and applying the paste-covered paper may be 40 readily and accurately performed; and to these ends my invention consists in certain novel features, which I will now proceed to describe, and will then specifically point out in the claims.

45 In the drawings I have shown a machine in which my invention is practically carried out in one form, in which—

A represents a suitable table upon which the various parts of the machine are supported. 50 Upon this table are mounted two frames, the

one, B, being preferably stationary, while the other, C, is mounted to slide in ways upon the table, as shown, so as to regulate its distance from the fixed frame B, a bolt, c, passing through a slot in the table and receiving a 55 nut, c' , by means of which the movable frame may be clamped after adjustment. In suitable bearings in the frame B is mounted a revolute spindle, D, having removably attached to its inner end a disk, d, provided with small 60 projections d' , three of these projections being shown in the present instance, though more or less than this number may be employed.

E indicates a spindle mounted in the frame C, with its axis in line with the axis of the 65 spindle D, and capable not only of revolution, but also of longitudinal movements in the line of its axis. This spindle is provided with a terminal disk, e, at its inner end, corresponding to the disk d of the spindle D. The disks 70 d and e are shown in the present instance as screwed upon the ends of their respective spindles, so that they may be readily removed when desired, but will rotate along with the spindles when in place.

Upon the spindle D is mounted a sleeve, F, 75 capable of longitudinal motion upon the spindle, but caused to rotate with it by means of a pin, d'' , upon the spindle, which enters a slot, f , in the sleeve, or by any other approved means. Upon the end of this sleeve, adjacent to the disk d , is secured a disk, F', of larger diameter than the disk d , and having a peripheral flange, f' , the whole forming a centering device, as hereinafter described.

Upon the spindle E is mounted a sleeve, G, 80 capable of longitudinal motion upon the spindle, and having attached to its inner end the box-holder G', consisting of a cylindrical body attached to a disk, which latter projects somewhat beyond the body and forms a terminal flange, g. Both the centerer and box-holder are shown as screwed upon their respective sleeves, so that they may be readily removed, though they may be otherwise attached, if desired.

H indicates a lever, which is pivoted at its rear end to the frame C and extends forward under the spindle E, to which it is connected by means of a screw or pin, h, attached to a 90 100

sleeve, e' , mounted on the spindle between two collars, so as to permit the spindle to revolve freely within the sleeve, but at the same time participate in the longitudinal motion imparted to the sleeve by the lever.

I indicates a second lever, also pivoted at its rear end to the frame C, and extending forward and connected by a pin, i , passing through a slot in the lever, to a sleeve, I' , mounted between collars on a rod, I^2 , which passes through the sleeve, and is itself mounted in the frame C, so as to be capable of longitudinal motion. A spring, i' , of rubber or metal, is arranged between the inner end of the sleeve I' and the adjacent collar, for the purposes hereinafter described. On the inner end of the rod I^2 is arranged a yoke, I^3 , constructed substantially as shown in Figs. 7 and 8 of the drawings, the said yoke being embraced between collars g' on the sleeve G, so as to allow the said sleeve to rotate freely, but to cause it to partake of the longitudinal motion imparted to the rod I^2 by means of the lever I. A stop, i'' , is secured upon the end of the rod I^2 , which projects beyond the frame C, the said stop limiting the inward motion of the rod by its contact with the frame, and consisting, preferably, of a sleeve provided with a set-screw, by means of which it can be secured at various points on the rod after adjustment.

The levers H and I extend outward over and rest upon the front bars, J, of the frame C, and these bars are provided with conical enlargements j , forming inclines terminating on the inner side in abrupt shoulders, so that the levers while in operation will ride over the said inclines and drop behind the shoulders, and thereby be locked to prevent any accidental return movement of the levers. An adjustable stop, j' , similar in construction with the stop i'' , is provided upon the lower bar, over which the lever H travels, to limit the movement of the said lever in an inward direction. A stop similar to the stop j' may be employed upon the upper bar J to limit the movement of the lever I, the stop i'' being dispensed with in that case; or, instead of the stop j' , a stop similar to the stop i'' may be arranged upon the end of the spindle E.

In order to render the fulcra of the levers H and I adjustable, for the purposes hereinafter described, these levers are pivoted to sleeves mounted loosely upon one of the rear cross-bars of the frame C, and secured after adjustment by set-screws in an obvious manner.

In order to impart a rotary motion to the spindle D, I mount upon the said spindle a large friction-pulley, K, and a small friction-pulley, k. The large pulley K is arranged immediately below a pulley, K' , of smaller diameter, mounted on a shaft, K^2 , journaled in arms K^3 , projecting from a rock shaft, K^4 , mounted in suitable bearings in the frame B. The shaft K^2 is operated by means of a belt, L, passing over differential pulleys l on the said shaft and upon the drive-shaft L'.

M indicates an arm attached to the rock-

shaft K^4 , and having pivoted to it the upper end of a connecting-rod, m, the lower end of which is attached to a foot-lever, M'. A spiral spring, m' , is arranged between the top of the table A and a stop, m'' , on the rod m, and exerts an upward pressure on the said rod, which keeps the friction-pulley K' somewhat above the pulley K in the position shown in the several figures of the drawings, except when the foot-lever M is depressed. Above the small pulley k is arranged a large friction-pulley, k' , mounted on a shaft, k^2 , journaled in arms k^3 projecting from a rock-shaft, k^4 , mounted in the frame D. This rock-shaft is provided with an arm, N, connected by a rod, n, to the foot-lever N', a spring, n' , being arranged to thrust the rod upward when the lever N' is not depressed, and thus hold the pulley k' normally out of engagement with the pulley k. Differential pulley l and a band, L, operate the shaft k^2 in the same manner that the shaft K^2 is operated.

Upon the rock-shaft K^4 and k^4 are secured arms K^5 , provided with set-screws k^5 , which come into contact with the frame B, or a cross-rod thereof, as shown, and serve to adjustably limit the upward throw of the arms M and N and their connected parts.

A cleaning-wheel, O, of felt, cloth, or other suitable soft material, is attached to the end of the shaft L' in the manner shown, for the purpose hereinafter described.

The operation of my device is as follows: The parts being in the position shown, a circular box-bottom is placed within the centerer F' and against the disk d, the centerer being of an internal diameter equal to the diameter of the box-bottom. By means of the lever H the spindle E is moved longitudinally to bring the clamping-disk e against the disk d, when by its pressure the box-bottom will be forced upon the points d' on the disk d to prevent its becoming uncentered in the subsequent operations. The lever H is then moved back to its former position, thereby withdrawing the disk e, the box-bottom being held in position within the centerer by means of the finger of the operator during this operation. The box-body, which consists of a plain cylindrical tube, is then placed upon the box-holder G', which is of a proper size to receive it, the flange g preventing the body from passing too far over the box-holder. By means of the lever I the box-holder G', carrying the box-body, is then moved up toward the spindle D, the projecting end of the box-body entering the centerer F' and bearing against the box-bottom, which is already in place. The clamping-disk e is then moved up by means of the lever H against the disk d, and the centerer F' is slid back upon the spindle D out of the way. The box body and bottom are now clamped in the same relative position which they will occupy in the completed box, and are therefore ready to receive the paper covering which unites them and completes the box. This paper covering consists of a strip of paper, or,

if desired, of two strips overlapping each other, the whole being of a width somewhat in excess of the length of the box, and being supplied with paste upon one side. This covering-paper may be supplied to the machine in strips of a sufficient length; or it may be drawn from a machine provided with a roll of paper and supplied with paste by passing over a suitable paste-roller. The end of this strip is laid over the box-body, which is rotated either by hand or by depressing the foot-lever M' , so as to bring the small friction-pulley K' in contact with the large friction-pulley K on the spindle D . This rotary motion of the box-body winds the paper around it, the end of the paper being turned over the projecting edge of the box-bottom by the operator during this rotation. It will be observed that the box-bottom, which is shown at P in Fig. 12, is somewhat greater in diameter than the box-body P' , and therefore projects out beyond it, leaving a corner, p , in which the paper covering p' must be forced. This laying on of the paper covering may be effected to a certain extent by hand; but for the finishing I employ the tool shown in Fig. 11 of the drawings. This consists of a suitable handle, Q , upon which is mounted a roller, Q' , consisting of a disk provided with a projecting hub, q , which is undercut next to the disk, forming a groove, q' . In conjunction with this roller-tool, I employ an adjustable tool-rest, R , of any approved construction, to support the tool while in operation. The paper covering, having been applied over the whole outer surface of the box-body and lapped over the end of the bottom, as hereinbefore described, by depressing the foot-lever N' the large friction-pulley k' is brought in contact with the small friction-pulley k on the spindle D , and a rapid rotary motion thereby imparted to the spindle, and consequently to the box, which is clamped against it. The roller-tool is then applied to the box at the junction of the bottom and body, the disk portion thereof resting against the under side of the bottom and the hub portion against the body, while the groove q' accommodates the projecting periphery at the bottom. The rotary motion imparted to the box brings all parts of the joint between the body and the bottom under the action of the roller-tool, which presses the paper covering properly into place. The connection between the body and the bottom being now complete, the box-holder G' is removed by throwing back the lever I , and the projecting end of the paper covering may be then turned down into the interior of the box by the operator, the box-body being supported during this operation by its connection with the bottom, which is clamped between the two disks. The lever H is then swung back and the complete box removed, when the machine is in position to again perform the series of operations above described. Any paste that accumulates upon

the roller-tool may be readily removed by holding the same against the continually-rotating cleaning-wheel O .

The clamping-disks, centerer, and box-holder are all detachable, so that they may be removed and others substituted when it is desired to adapt the machine to the construction of a different-sized box, and sets of these parts may be constructed to fit any sized box which it is desired to make. In case the box-body be longer or shorter, the frame C may be moved farther away from or nearer to the frame B , according to the length of body desired. The relative position which the movable clamping-disk and box-former occupy at the extreme limits of their motion, both with respect to each other and with respect to the fixed clamping-disk, may be varied at will by adjusting the fulcrum of the levers H and I , as hereinbefore described. The spring i' , interposed between the sleeve I' and the collar on the rod I^2 , will, in case the box-body on the box-holder is of a greater length than that for which the machine is set, yield to the advance of the lever, when the box-holder and rod I^2 can no longer advance, and allow the lever to pass over the locking-cone j without crushing the box-body.

It is obvious that various mechanical modifications may be made in the construction shown and described without departing from the principle of my invention. For instance, both frames may be made adjustable or both may be fixed, or the frame B made adjustable and the frame C fixed. Although I have shown a preferred form of mechanism for imparting either a slow or a rapid motion to the spindle D , it is obvious that other mechanism may be employed to rotate the said spindle, if desired. The machine may readily be adapted to the construction of square or polygonal boxes by constructing the clamping-disks, centerer, and box-holder of the proper shape. Although the machine is especially well adapted for the construction of boxes of the description shown in Fig. 12 of the drawings, having a bottom projecting out beyond the body of the box, still it is evident that the machine is also adapted to the construction of boxes in which the bottom is of a diameter equal to the external diameter of the body, or in which the bottom is equal to the internal diameter of the body, and is placed within the same. I therefore do not wish to be understood as limiting myself strictly to the precise construction hereinbefore described, and shown in the drawings.

Having thus described my invention, what I claim as new, and desire to secure by Letters Patent, is—

1. In a paper-box machine, a fixed revolute spindle carrying a clamping-disk, in combination with a movable revolute spindle carrying a similar clamping-disk, and a holder for carrying the box-body mounted and inde-

- pendently adjustable upon the movable spindle, substantially as and for the purposes specified.
2. In a paper-box machine, the combination, with a fixed revoluble spindle carrying a clamping-disk and mounted in a suitable frame, of a movable spindle carrying a similar disk and a box-holder, and also mounted in a suitable frame, one of said frames being adjustable to and from the other, substantially as and for the purposes specified.
3. In a paper-box machine, a fixed revoluble spindle provided with a clamping-disk and a centerer, in combination with a movable revoluble spindle carrying a similar clamping-disk, and a holder for carrying the box-body mounted and independently adjustable upon the movable spindle, substantially as and for the purposes specified.
4. The combination, with the spindle E, of the sleeve G, carrying a box-holder, G', rod I², having yoke I³, fitting between collars g' on the sleeve G, and lever I, substantially as and for the purposes specified.
5. The combination, with the box-holder and the sliding rod which operates the same, of a lever adapted to operate the sliding rod, and a safety-spring connection between the lever and rod, substantially as and for the purposes specified.
6. The combination, with the box-holder and the rod I², which operates the same, of the sleeve I', arranged between collars on the said rod, the spring i', arranged between the said sleeve and one of the collars, and the lever I, connected to the said sleeve, substantially as and for the purposes specified.
7. The combination, with the clamping-disk and box-holder and the levers which operate the same, of the bars J, having the conical enlargements j to lock the said levers, substantially as and for the purposes specified.
8. The combination, with the spindle and clamping-disk, of the box-holder and sliding rod, levers connected to the said spindle and sliding rod to move them longitudinally, and stops to limit the inward motion of the said parts, substantially as and for the purposes specified.
9. In a paper-box machine, the combination, with the spindle to which the work is clamped and the drying-shaft, of two sets of friction-

wheels arranged between the said shaft and spindle, one constructed to give the spindle a rapid and the other constructed to give the spindle a slow rotary motion, substantially as and for the purposes specified.

10. In a paper-box machine, the combination, with the rotary spindle to which the work is clamped, provided with a large and a small wheel, of a small and large wheel arranged, respectively, above the wheels on the spindle and mounted in separate hinged frames capable of being depressed to cause either of the said wheels to engage with the corresponding wheel on the spindle, substantially as and for the purposes specified.

11. In a paper-box machine, the combination, with the spindle D, to which the work is clamped, the said spindle being provided with a friction-wheel, K, of a friction-wheel, K', secured on a shaft suitably connected with the drive-shaft and mounted in the arms of the rock-shaft, the said arms being capable of being depressed to cause the wheel K' to engage with the wheel K, substantially as and for the purposes specified.

12. In a paper-box machine, the combination, with the work-holding spindle D, having wheels K k, of the wheels K' k', mounted on shafts K² k², suitably connected with the drive-shaft, rock-shafts K⁴ k⁴, having arms K³ k³, in which the said shafts are mounted, and arms M and N, to which are attached the rods m n, and springs arranged to thrust the said rods m n normally upward, substantially as and for the purposes specified.

13. The combination, with the clamping-disk and box-holder and the spindle and sliding-rod to which they are connected, of levers connected to the said spindle and sliding rod and adjustably pivoted to the frame, substantially as and for the purposes specified.

14. The combination, with the sliding rod and spindle, of levers connected to the said sliding rod and spindle and pivoted to sleeves adjustably secured by set-screws on a cross-bar of the frame, substantially as and for the purposes specified.
